SAFETY DEVICE FOR MINE CARS

John Pugh, Pennington Gap, Va., assignor of
forty-nine per cent to Earl P. Smyth, St.
Charles, Va.

Application August 15, 1939, Serial No. 290,287

3 Claims. (Cl. 188—38)

The present invention relates to new and useful improvements in safety devices for mine cars and has for its primary object to provide, in a manner as hereinafter set forth, an automatic brake of a novel construction and arrangement which is adapted for attachment to the rear end of a trip or train of cars and which will positively prevent said cars from rolling back down a hill in the event that any of them should 10 accidentally break loose.

Another very important object of the invention is to provide an automatic safety device of the aforementioned character which is adapted to be conveniently connected to a mine car 15 or removed therefrom when desired.

Other objects of the invention are to provide a safety device for mine cars of the character described which will be comparatively simple in construction, strong, durable, highly efficient and 20 reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in side elevation of a mine 30 car, showing a device constructed in accordance with the present invention connected thereto.

Figure 2 is a view in vertical longitudinal section through the device.

Figure 3 is a top plan view of the device.

Figure 4 is a bottom plan view.

Figure 5 is a cross sectional view, taken substantially on the line 5—5 of Fig. 2.

Figure 6 is a cross-sectional view, taken substantially on the line 6—6 of Fig. 2.

Referring now to the drawings in detail, it will be seen that the embodiment of the invention which has been illustrated comprises a metallic dog 1 which is substantially similar in cross sectional shape to a conventional railroad rail. The dog 1 is provided with a beveled forward end 2 and a rounded rear end 3.

Jounaled in a suitable bearing 4 on the forward end portion of the dog 1 is a transverse pin 5. The reference numeral 6 designates a coupling link through the medium of which the dog 1 is pivotally and detachably connected to the rear end of a conventional mine car, as at 7. The link 6 is adapted to receive the usual pin 8 of the car 7. The ends of the link 6 are secured to the end portions of the pin 5 by

substantially U-shaped straps 9. At least one of the straps 9 is fixed, as by welding, to the pin 5 for preventing loss of said pin.

It will thus be seen that the dog 1 is connected to the rear end of the mine car 7 for swinging movement in a vertical plane. Rising from the forward end of the dog 1 is a T-member 10 which limits the upward swinging movement of the link 6 on the dog 1. A carrying and attaching handle 11 is provided on the forward portion 10 of the dog 1, the forward end of said handle being fixed to the T member 10.

Mounted on the forward portion of the dog 1 is a substantially triangular brace 12 of suitable metal which is engageable with a frame member 15 of the mine car 7 for supporting said dog 1 against twisting or turning. As illustrated to advantage in Fig. 5 of the drawings, the brace 12 extends beneath the base or lower portion of the dog 1 and has its intermediate portion welded thereto, the ends of said brace being welded to the ball or upper portion of said dog 1.

Fixed longitudinally on the bottom of the dog 1 immediately to the rear of the brace 12 is a substantially triangular metallic stop 13 which is engageable beneath the aforementioned car frame member for preventing bending of the draw bar and for driving the dog into the ground between the ties. The stop or lug 13 is laterally braced or reinforced, as at 14.

It is thought that the manner in which the device functions will be readily apparent from a consideration of the foregoing. As the car 7 moves forwardly the dog 1 is dragged therebehind, said dog being pulled across the ties 15 of the track 16. Should one or more of the cars of the train or trip break loose and start to roll back down the hill the dog 1 is driven into the road bed against one of the ties 15 for arresting and positively holding the cars. As hereinbefore stated, the brace 12 is adapted to bear against a frame member of the car for supporting the dog 1 against twisting or turning movement while the stop or lug 13 is adapted to engage beneath said frame member for preventing the draw bar from being damaged and for driving said dog into the ground. The construction and arrangement is such that the device may be expeditiously attached to the mine car even while the train or trip is moving.

It is believed that the many advantages of an automatic safety device for mine cars constructed in accordance with the present invention will be readily understood and although a preferred embodiment of said device is as illustrated 55

and described, it is to be understood that changes in the details of construction and in the combination and arrangement of parts may be resorted to which will fall within the scope of the 5 invention as claimed.

What is claimed is:

1. A safety device of the character described for mine cars of the type including a frame, comprising a dog, means for pivotally connecting one end portion of said dog to a mine car, and a substantially triangular brace mounted transversely on the pivoted end portion of the dog and adapted for abutting engagement with a member of the frame of the mine car for supporting said dog against turning movement, and a stop mounted longitudinally beneath the dog rearwardly of the brace and engageable beneath the frame member of the mine car when said dog is in operative position.
- 10 2. A safety device of the character described for mine cars of the type including a frame, comprising a dog, means for pivotally connecting said dog at one end to a mine car for swinging movement in a vertical plane, a substantially

triangular brace mounted transversely on the pivoted end portion of the dog and adapted for abutting engagement with a member of the frame of the mine car for supporting said dog against turning movement, and a stop mounted longitudinally beneath the dog rearwardly of the brace and engageable beneath the frame member of the mine car when said dog is in operative position.

3. A safety device of the character described for mine cars comprising a dog, a substantially U-shaped link pivotally mounted for swinging movement in a vertical plane on one end portion of said dog and adapted for connection with a mine car, a T-member fixed on said one end portion of the dog and engageable with said link for limiting the swinging movement of same in one direction relative to the dog, and a handle mounted on the dog and having one end secured to said T-member.

JOHN PUGH. 20
